ELECTROMAGNETIC DEVICE

Charles F. Warrick, Detroit, Mich., assignor to
 Bender-Warrick Corporation, Birmingham,
 Mich., a corporation of Michigan

Application September 21, 1936, Serial No. 101,710

5 Claims. (Cl. 175—338)

This invention relates to electromagnetic devices, and has to do especially with devices of the type where an armature or the like is to be attracted into abutting relationship with another element which serves as a stop, and which may be the core piece of the electromagnet. The invention is particularly applicable to devices of this type utilizing alternating current, although the invention may be used with direct current and may be useful where the direct current is pulsating. In this class of devices are such items as relays, motor starters, vibration devices, electrical controlling devices, etc.

The principal object of the invention is to provide a device of the character mentioned which will give a quietness of operation, and which will eliminate many of the troubles and difficulties and problems heretofore encountered in an effort to construct such devices so that their operation is quiet or noiseless.

Heretofore in electromagnetic devices arranged to be used with alternating current the so-called shading coils have been employed with the view of minimizing the vibration or hum due to the alternate setting up and breaking down of the flux. Briefly, these shading coils delay some of the flux so that when the flux through the unshaded portion is at zero, the delayed flux serves to keep the armature attracted. These devices are only a partial remedy from the standpoint of the objects to be attained by the present invention. The present invention may be used with shading coils, with the view of more or less evening out the flux curve.

Where a solid armature strikes a solid stop or core piece, there is a resultant blow which creates noise. This is particularly true where the abutting surfaces do not come together evenly, or in other words where there are one or more high spots which take the initial blow. Much work has heretofore been done on these devices in machining and grinding the surfaces but this leads to difficulty in that, if the surfaces are very accurately ground for surface to surface contact to eliminate noise, then the two pieces, namely, the armature and the stop, tend to stick together when the magnet no longer attracts the armature. This action may be likened to a suction cup, as the surfaces meet so perfectly that practically an air tight contact is obtained and the vacuum condition created prevents the armature from being released. This is a bad condition because the force required to release the armature is too great as the force has to be overcome the next time the magnet is to attract the armature.

Then, too, a piece of dirt or other extraneous matter may get in between the surfaces and a noise condition created which gets greater in use. Moreover, the battering of the surfaces may soon destroy the accuracy of the machining so that a noise condition results. Sometimes the device has been mounted in rubber to minimize the transmission of noise through metallic parts, and to cut down the hum which may be present where alternating current is used.

Devices of this type for use with alternating current are usually constructed of laminations so as to reduce as much as possible the so-called eddy currents which may be induced in the iron cores by the alternating magnetic flux. This form of construction, namely, the laminated construction, may be advantageously employed in carrying out the present invention. However, in the prior laminated structures the laminations were tightly bolted or riveted together so that in effect the core and armature constituted one solid metal mass, so far as the function in contacting each other is concerned. The laminations performed no function from a noise-minimizing standpoint, but were merely to minimize the eddy currents.

In carrying out the invention the armature or stop element against which the armature is attracted, which may be the pole pieces of a magnetic core, or both, are made up of a plurality of more or less loosely associated or relatively movable pieces. The armature, for example, may be made of a plurality or a multiplicity of separate pieces, capable of movement relative to each other so that when the armature strikes a stop or pole the several pieces may adjust themselves or seek their own seat against the surface of the stop. Thus, if there is a high point in the contact this point may affect only one piece of the armature and does not take the blow of the entire armature, and in this action the other pieces seek their own individual seats, whether on a high spot or a low spot.

In carrying out the invention a laminated structure may be employed but the laminations are so associated with each other that they are relatively movable so that each lamination acts as a separate piece and can find its own seat or adjust itself to the particular portion of the stop or member against which it is to abut. This structure may be incorporated in the armature, or a stop such as the core of the electromagnet, or both.

In the accompanying drawing:

Fig. 1 is a general view illustrating an electro-

magnetic device comprising a core and an armature and constructed in accordance with the invention.

Fig. 2 is a side elevational view looking substantially on line 2-2 of Fig. 1.

Fig. 3 is a cross-sectional view of the armature looking substantially on line 3-3 of Fig. 1.

Fig. 4 is a detail of one form of spring which may be used.

Fig. 5 is a view similar to Fig. 3 showing the loose laminated structure incorporated in the core.

Fig. 6 is a cross-sectional view through the laminations of an armature or the like illustrating rounded contact surfaces.

In Fig. 1 the core of an electromagnet is illustrated generally at 1, the core being in the form of an A. This core may be made up of laminations as illustrated in Fig. 2 secured together by means such as rivets 2. The core shown is one which has a primary coil 3 which may be constantly connected to an alternating current line and the cross bar 4 constitutes a magnetic shunt. Around the shunt is a coil 5 connected to leads 6. The pole pieces of the core are illustrated at 7. Now this is merely exemplary of one kind of core which may be used and is of the type shown in my Patent No. 1,979,127 of October 30, 1934. The function is briefly as follows: The alternating current in the coil 3 continuously sets up alternating flux which is shunted through the shunt 4 so that the same is ineffective to attract the armature. The leads 6 may extend, for example, to a controlling device such as electrodes or a thermostat, or the like (not shown) which upon certain conditions closes the circuit through the coil 5. Coil 5 then serves as a choke for the shunt 4 and the flux set up by the coil 3 seeks a path across the poles and attracts the armature. This brief description is merely given to indicate how the armature, soon to be described, is attracted, although it is to be emphasized again that the invention is not limited to an electrical hook-up which operates in this manner, as any type of electromagnetic device may be used with the invention.

The armature is generally illustrated at 10 and it may be pivotally mounted so that it is substantially balanced on an arm 11 in turn pivoted as at 12, and the armature may be normally held away from the poles by a spring 13, or for that matter the armature may merely gravitate away from the poles.

As shown in Fig. 3, the armature has a laminated body composed of laminations 15 such as a series of iron or steel plates or strips lying in superposed condition.

Now these laminations are arranged so that they are shiftable relative to each other and are not bolted down tight. One way of constructing the armature to this end is illustrated in Fig. 3, this being merely exemplary of one form of structure for carrying out the invention. This structure includes side supporting plates 16 with pins 17 passing through apertures therein. The laminated plates may be mounted on relatively soft rubber sleeves 18 which extend through the laminations as shown, and the pins 17 may extend through the sleeves. A leaf spring 19 of curved form may be placed between each supporting plate 16 and the laminated body, the springs acting to press the laminations together with spring pressure and reacting against the side plates. These springs may have notched 75 ends as shown at 20 for fitting over the end pins

and rubber bushings while the central portion may be apertured as at 21 for the reception of the center pin. The assembly may be completed by the use of spring clips of suitable structure as shown at 22 clipping over the ends of the pins opposite their headed ends, and a washer 23 may be placed between some of the clips and a side plate. In the form shown the arm 11 in reality is constituted by two spaced arms fulcrumed on the center pin 17.

Now this structure may be incorporated in the core, as illustrated in Fig. 5 where it will be seen that the core is made up of a body of laminations 25, side plates 26, pins 27 with rubber bushings 28 and springs 29, the assembly being completed by the clips 30.

When the armature is attracted and strikes the poles 7 the body of the armature composed of the loose laminations is flexible, the several laminations adjusting themselves so as to seat upon the surfaces of the poles, regardless of whether or not the seating surface is regular or irregular. As the laminations adjust themselves the rubber of the sleeves 18 is distorted and flows to permit such action. The function may be likened to a single lamination striking the poles and it will readily be appreciated that there is no particular noise or pounding action because of the light weight of the single lamination. The several laminations act individually in this respect. If one lamination strikes the poles first it does not take the impact caused by the movement and inertia of the entire armature. It merely comes to its own seat and then the other laminations come to their seats. The same action is obtained if the structure is incorporated in both the armature and core, or only in the core. Thus if the contacting surfaces are not accurately machined the armature, being self-aligning so to speak, seats properly thereon. If any extraneous matter or a piece of dirt gets in between the abutting surfaces the parts merely adjust themselves to meet this situation. The structure also meets a situation where there is warpage in the parts which may destroy the initial proper alignment. The armature and pole pieces will not stick together even if they are very accurately machined and finished for a perfect seat, because air can get in between the laminations so as to break any vacuum tendency. In fact it has been found that the contacting edges of the laminations need not be flat, but may be rounded. This is illustrated in Fig. 6 where the rounded contacting edges of the laminations are shown at 31.

The above description clearly sets forth how the quiet operation is obtained, and it will be appreciated that the particular structure shown is exemplary of the principle involved in this invention. It will likewise be understood that the invention may be used together with shading coils where it is desirable to even out the flux curve where alternating current is used.

I claim:

1. An armature for an electromagnetic device comprising, a plurality of facing laminations, spring means packing the laminations together, and rubber elements passing through the laminations and which are flexible, whereby the laminations may shift individually and adjust themselves to a surface against which the armature is attracted.

2. An armature for an electromagnetic device comprising, an armature body made up of a plurality of laminations, supporting side plates,

pins carried by the supporting side plates and extending through the laminations, rubber sleeves over the pins supporting the laminations so that they are shiftable edgewise relative to each other by the flexible action of the rubber, and spring means between the supporting plates and laminated body for packing the laminations together.

3. An electromagnetic device comprising in combination a core, a freely movable armature positioned away from the core and mounted to be attracted bodily thereby and to move bodily away therefrom upon magnetic flux variation in which action the armature strikes and abuts against a surface of the core or other stop, said armature comprising a plurality of laminations lying in planes substantially at right angles to said surface or stop and substantially parallel to said movement for direct contact with the surface or stop with their edge portions, flexible means for holding said laminations together so that they normally move as a body, said means arranged to flex so that individual laminations may adjust themselves individually to the said surface or stop when attracted thereagainst magnetically.

4. An electromagnetic device comprising in combination a core, a freely movable armature positioned away from the core and arranged to be bodily attracted thereby and to move bodily away therefrom upon magnetic flux variation, in which action the armature strikes and abuts

against a surface of the core or other stop, said armature comprising a plurality of laminations lying in planes substantially at right angles to said surface or stop and substantially parallel to the movement for direct contact with the surface or stop with their edge portions, means for holding said laminations against each other with tension so that they normally move as a body, and means passing through the laminations transversely to the planes in which the laminations lie arranged to permit individual laminations to shift in their planes relative to each other whereby individual laminations may adjust themselves individually to said surface or stop when attracted thereagainst magnetically.

5. An electromagnetic device comprising in combination a core having pole pieces, an armature, means mounting the armature for bodily movement toward and away from the core incident to magnetic flux with the armature arranged to strike the pole pieces, said armature comprising a plurality of laminations disposed at right angles to the surfaces of the poles which the armature is adapted to strike, means resiliently holding the laminations of the core together so that the individual laminations may shift relative to each other whereby individual laminations may directly contact with and adjust themselves in seating relation on the armature when the armature is in contact therewith.

CHARLES F. WARRICK.
